US00D864958S

(12) **United States Design Patent** (10) **Patent No.:** **US D864,958 S**
Yüksek et al. (45) **Date of Patent:** **** Oct. 29, 2019**

(54) **ELECTRONIC INFORMATION TERMINAL**(71) Applicant: **Arçelik Anonim Sirketi**, Tuzla, Istanbul (TR)(72) Inventors: **Tamer Yüksek**, Istanbul (TR); **Özlem Kök**, Istanbul (TR); **Can Onur Vancı**, Istanbul (TR); **Ece Çınar**, Istanbul (TR); **Aslı Ökmen**, Istanbul (TR); **Doğaç Can Sağirosmanoğlu**, Istanbul (TR); **Nihat Duran**, Istanbul (TR); **Gizem Durakoğlu**, Istanbul (TR)(73) Assignee: **Arçelik Anonim Sirketi**, Istanbul (TR)(**) Term: **15 Years**(21) Appl. No.: **29/636,068**(22) Filed: **Feb. 6, 2018**(30) **Foreign Application Priority Data**Aug. 10, 2017 (EM) 004142404

CLAIM

The ornamental design for an electronic information terminal, as shown and described.

DESCRIPTION

FIG. 1 is a front, right perspective view of an electronic information terminal showing our new design;

FIG. 2 is a front elevation view thereof;

FIG. 3 is a top plan view thereof; and,

FIG. 4 is a side elevation view thereof, the opposite side being a mirror image thereof.

1 Claim, 3 Drawing Sheets

FIG. 1

FIG. 2

FIG. 3

FIG. 4
